DESIGN FOR A DISPLAY CABINET

Leslie R. Wieslander, Oakland, Calif., assignor to
The Cincinnati Ball Crank Co., Cincinnati,
Ohio, a corporation of Ohio

Application January 7, 1937, Serial No. 66,939

Term of patent 14 years

To all whom it may concern:

Be it known that I, Leslie R. Wieslander, a citizen of the United States, residing at Oakland, in the county of Alameda and State of California, have invented a new, original, and ornamental Design for a Display Cabinet, of which the following is a specification, reference being had to the accompanying drawing, forming a part thereof.

The back view of the design is substantially the same as the front. The dominant feature of the design resides in the appearance thereof as viewed from the front.

I claim:

The ornamental design for a display cabinet substantially as shown and described.

LESLIE R. WIESLANDER.
